CHARLES B. GEARING, OF PITTSBURGH, PENNSYLVANIA.

INTERNAL-COMBUSTION ENGINE.

1,100,068.

Specification of Letters Patent. Patented June 16, 1914.

Application filed April 20, 1912. Serial No. 692,075.

To all whom it may concern:

Be it known that I, CHARLES B. GEARING, a citizen of the United States, residing at Pittsburgh, in the county of Allegheny and State of Pennsylvania, have invented certain new and useful Improvements in Internal-Combustion Engines, of which the following is a specification.

The invention relates to internal combustion engines, and particularly to engines of the four cycle type. It has for its primary objects; the provision of a sleeve valve mechanism of a simplified and improved form; and the provision of a simplified and improved means for giving the valve the movements necessitated by its construction and the arrangement of the ports and by the character of the cycle. The invention is capable of a large number of different embodiments, two of such embodiments being for the purpose of illustration shown in the accompanying drawing, wherein—

Figure 1 is a longitudinal section through an internal combustion engine constructed in accordance with my invention, Fig. 2 is a transverse section on the line II—II of Fig. 1, Fig. 3 is a section through an engine having a modified form of valve operating means, and Fig. 4 is a side elevation of the valve sleeve employed.

Referring first to the particular embodiment of the invention as illustrated in Fig. 1, the principal parts may be enumerated as follows: 1 is the cylinder casing provided with a water jacket 2; 3 is the cylinder head also water jacketed and having a cylindrical portion 4 projecting down into the cylinder, but with its walls spaced away from the walls of the cylinder; 5 is a valve sleeve for controlling the admission and exhaust; 6 is a piston working inside the valve sleeve 5; 7 is the crank shaft of the engine, provided with the usual crank 8 connected to the piston 6 by means of the connecting rod 9; and 10 is the crank casing.

The cylinder casing 1 is provided with an inlet passage 11 which inlet passage communicates with the inlet port 12, such port being in the form of a groove which extends completely around the interior of the cylinder casing. The exhaust passage 13 communicates with the exhaust port 14, which port 14 is in the form of a groove upon the interior of the cylinder casing and extending completely around such casing. The valve sleeve 5 has one set of perforations or

ports only for registering alternately with the inlet and exhaust ports 12 and 14, such perforations or ports in the valve sleeve being in the form of a series of slots 15 placed in alignment end-to-end, and taken together extending clear around the sleeve, the separate slots being separated only by the bridge portions 16 (Fig. 4).

The mechanism whereby the sleeve 5 is operated to give the four cycle timing constitutes one feature of my invention and will now be described. A crank shaft 17 extends into the crank casing 10 and carries the crank 18. This crank shaft 17 carries upon its outer end and outside of the crank casing the spur gear 19 which meshes with a spur gear 20 having one-half the pitch diameter of the gear 19 and mounted upon the crank shaft 7. Pivoted upon the crank 18 is a link 21, which link 21 is pivoted at its inner end to the inner end of a second link 22, the outer end of such latter link being pivoted to the valve sleeve 5 as indicated in Fig. 1. Another crank shaft 23 is mounted in the casing 10 and provided with a crank 24 carrying one end of the link 25, the other end of such link 25 being pivoted to the links 21 and 22 at their juncture 26. Shaft 23 carries a sleeve 27, and in this sleeve works a rod 28 pivoted at 29 to the connecting rod 9.

It will be seen from the foregoing that every time the crank shaft 7 rotates once the shaft 23 is rotated once, and the link 25 reciprocated, and that every time the crank shaft 7 rotates twice the shaft 17 rotates once. As a result the sleeve reaches its extreme upper position with its ports 15 in registration with the exhaust port 14 only once for each two revolutions of the crank shaft 7, and the sleeve reaches its lowermost position with its ports 15 in registration with the inlet port 12 only once for two revolutions of the crank shaft 7, the ports 15 in the period between these two extreme positions occupying a position somewhere between the ports 12 and 14, and cut off from communication therewith. This arrangement secures the four cycle timing desired.

Starting with the parts in the position indicated in Fig. 1, the operation is as follows: At this time the ports 15 in the sleeve register with the exhaust port 14 and exhaust is occurring. At this time also the shafts 17, 7 and 23 are turning in the direc-

tion indicated by the arrows, and the piston 6 is rising and thus expelling the products of combustion from the cylinder. The sleeve 5 maintains approximately the position 5 shown until the shaft 7 turns a little over 90° and the shaft 23 makes a corresponding rotation. A further rotation of the shafts 7, 17 and 23 causes the sleeve 5 to move down rapidly until the ports 15 register with 10 the inlet port 12, at which time the upper end of the piston is just passing such port 12. The ports 15 remain in registration with the port 12 until the crank 8 reaches a position at substantially 270° from the 15 position shown, at which time the piston 6 is in its lowermost position and the crank 24 is moving to the left, thus tending to bring the links 21 and 22 into alinement and raise the ports 15 out of registration 20 with the port 12. The upward movement of the piston 6 compresses the charge in the sleeve and ignition occurs in the usual manner when the piston reaches its uppermost position, the ports 15 being during the upward movement of the piston 6 and its subsequent downward movement when the gases are exploded blanked with respect to the ports 12 and 14, such result being secured by reason of the fact that the crank 25 30 18 is during this period in a position below the shaft 17. At this time, however, the crank 18 is moving upward, and the crank 24 is moving to the right, so that the sleeve is rapidly raised to the position shown in 35 Fig. 1, at which time the exhaust port 14 is brought into communication with the port 15, thus completing the cycle.

The exterior of the sleeve 5 is provided with a plurality of depressions or pits 30, 40 (Fig. 4) in order to receive and hold oil, thus providing for the lubrication of the outer surface of the sleeve in the cylinder casing 1. Oil is carried up to the sleeve in the usual way by means of the scoop 31 carried by the connecting rod, such scoop dipping into the oil trough 32 upon each revolution of the crank shaft. This trough 32 is supported by means of a pair of parallel links 33 and 34, so that when the trough is 45 lifted to regulate its height and the amount of oil drawn therefrom by the scoop 31, such trough will always maintain a horizontal position. The link 34 is connected to the throttling mechanism by means of link 35 50 and other mechanism which is not shown, so that as the speed of the engine increases the trough 32 is raised and the amount of oil supplied is increased.

The cylinder casing 1 supports the sleeve 5 throughout substantially the entire length exposed to pressure, and is kept cool by means of the water jacket 2. A siphon tube 36 is provided for the drainage of the water space in the head 3, such tube having its 55 short leg in the head and its long leg in the

jacket 2, so that when the jacket 2 is drained from its lower portion the head will also be drained. The portion 4 of the head 3 serves as a guide and support for the inner surface of the sleeve 5, and is made tight with 70 respect to such sleeve by means of packing rings 37 and 38 placed above and below the perforations 39 by which communication is had with the ports 15 in the sleeve and the port 14 in the cylinder casing.

While the spur gears 19 and 20 are illustrated as providing for the transmission of power from the shaft 7 to the shaft 17 in a two-to-one ratio, it will be understood that other forms of driving mechanism may be employed, as for instance a pair of gears or sprockets with a connecting chain, such form of mechanism being illustrated in Fig. 3. It will also be understood that other forms of cranks such as an eccentric may be substituted for the cranks 18 and 24 if desired, as illustrated in Fig. 3, and that the term "crank" as used in the claims is used in its generic sense to include eccentrics as well as cranks. Various other modifications 80 90 may also obviously be made without departing from the spirit of the invention as broadly defined and claimed.

The construction of Fig. 3 differs from that of Fig. 1 primarily in the means for giving the sleeve 5 its proper movement, an eccentric and a chain drive being substituted for the spur gear drive of Fig. 1. In this construction of Fig. 3 the crank shaft 7' carries a sprocket 40, and from this sprocket 100 40 the sprocket 42 is driven by means of the chain 43. The shaft 45 which carries the sprocket 42 is provided with an eccentric 47, such eccentric performing the functions of the crank 18 in the construction of Fig. 1. 105 The links 21' and 22' correspond to the links 21 and 22 of Fig. 1, and the link 25' corresponds to the link 25 of Fig. 1, the operation of the said link 25' from the connecting rod being the same as in the construction of Fig. 1.

Having thus described my invention and illustrated its use, what I claim as new and desire to secure by Letters Patent, is the following:

1. In combination in a four cycle internal combustion motor, a cylinder casing having adjacent its outer end an exhaust port and inwardly from such port and spaced away therefrom an inlet port, a valve sleeve fitting inside the cylinder and having adjacent its outer end a perforation, a piston in the sleeve, a crank shaft, a connecting rod intermediate the piston and crank shaft, and means for reciprocating the sleeve comprising a crank, means for rotating the crank once for every two revolutions of the crank shaft, a pair of links pivoted together at their inner ends with the outer end of one link pivoted to the sleeve and the outer end 115 120 125 130

of the other carried by the crank, and a connection from a point intermediate the ends of the connecting rod to the inner connected ends of the links whereby such inner ends are reciprocated transversely on each reciprocation of the connecting rod.

2. In combination in a four cycle internal combustion motor, a cylinder provided with admission and exhaust ports, a valve for controlling the admission and exhaust through such ports, a piston, a crank shaft, a connecting rod intermediate the piston and the crank shaft, and means for moving the valve, comprising a crank, means for rotating the crank once for every two revolutions of the crank shaft, a pair of toggle links pivoted together at their inner ends with the outer end of one link pivoted to the valve and the outer end of the other link carried by the crank, and a connection from a point intermediate the ends of the connecting rod to the inner connected ends of the links whereby such inner ends are reciprocated transversely on each reciprocation of the connecting rod.

3. In combination in a four cycle internal combustion motor, a cylinder provided with admission and exhaust ports, a valve for controlling the admission and exhaust through such ports, a piston, a crank shaft, a connecting rod intermediate the piston and the crank shaft, and means for moving the valve, comprising a crank, means for rotating the crank once for every two revolutions of the crank shaft, a pair of toggle links pivoted together at their inner ends with the outer end of one link pivoted to the valve and the outer end of the other link carried

by the crank, a crank adjacent the line of movement of the connecting rod, a sliding connection between the crank and connecting rod whereby the movement of the connecting rod causes a rotation of the crank, and a connection between the crank and the inner connected ends of the links.

4. In combination in a four cycle internal combustion motor, a cylinder casing having an exhaust port and spaced away therefrom an inlet port, a valve sleeve fitting inside the cylinder and having adjacent its outer end a perforation, a piston in the sleeve, a crank shaft, a connecting rod intermediate the crank shaft and piston, means operated from the connecting rod and the crank shaft to cause the said perforation to register with the inlet port once during two revolutions of the crank shaft to permit the admission of an explosive charge and to register with the exhaust port once during two revolutions of the crank shaft, the said perforation lying in the period between the closing of the inlet port and the opening of the exhaust port in a position intermediate such ports, the said means for operating the sleeve comprising a two link toggle, a connection from the crank shaft for shifting the position of the end of one of the links, and a connection from the connecting rod to the juncture of the two links.

In testimony whereof I have hereunto signed my name in the presence of the two subscribed witnesses.

CHARLES B. GEARING.
